UNITED STATES PATENT OFFICE.

CHARLES I. DODSON, OF PITTSBURG, KANSAS, ASSIGNOR OF ONE-FOURTH TO HARRY S. CLARK, ONE-EIGHTH TO ARCHIBALD T. CHEATHAM, AND ONE-EIGHTH TO JOSEPH FLETCHER, OF PITTSBURG, KANSAS.

INCANDESCENT LAMP.

966,812.

Specification of Letters Patent.

Patented Aug. 9, 1910.

Application filed April 9, 1909. Serial No. 488,864.

To all whom it may concern:

Be it known that I, CHARLES I. DODSON, a citizen of the United States, residing at Pittsburg, in the county of Crawford and 5 State of Kansas, have invented a new and useful Incandescent Lamp, of which the following is a specification.

This invention has reference to improvements in incandescent electric lamps and is 10 designed to produce an incandescent lamp the filament of which has a plurality of external connections so arranged that should the filament or portions of the filament in use burn out or become broken through some 15 cause, the lamp may still be as serviceable as ever by removing one of the external circuit terminals and exposing another leading to the unbroken portion of the filament.

The invention will be best understood 20 from a consideration of the following detail description taken in connection with the accompanying drawings forming a part of this specification in which drawings,

Figure 1 is a side elevation of an incandescent lamp constructed in accordance with the present invention. Fig. 2 is a central longitudinal section of the base end of the lamp on a larger scale than shown in Fig. 1, and Fig. 3 is a detail view showing another 30 arrangement of the filament.

Referring to the drawings there is shown a lamp 1 of ordinary construction so far as the general external appearance is concerned, and this lamp is provided with a filament 2 so 35 coupled up as to represent two or more useful filaments each giving the desired standard candle-power in light. The lamp is provided with the usual screw base 3, in the drawings shown as of the ordinary Edison 40 type but it will be understood that any other suitable type of base may be used. Since the lamp in its general structure may be such as is ordinarily employed no detail description of the general structure is deemed 45 necessary.

In the particular construction shown the lamp is provided with three leading-in wires 4, 5 and 6, but more leading-in wires may be used if deemed necessary. Under ordinary 50 circumstances three of these leading-in wires will be found sufficient. One of the leading-in wires say the central wire 4 is carried to the screw shell of the base as is customary in lamps of this type. In the

particular structure shown the leading-in 55 conductor 4 is connected to the central portion of the filament 2 while the ends of this filament are connected to the two conductors 5 and 6 and each of these conductors is carried through the base 3 and is there secured 60 to a plate 7 or 8 as the case may be, the conductor 5 being shown as connected to the plate 7 and the conductor 6 to the plate 8. It is the usual custom in lamps of this type 65 to carry the one terminal of the filament to a leading-in conductor to a plate concentric with the longitudinal central axis of the lamp, and this plate is made a permanent 70 part of the lamp base. With a lamp constructed in accordance with the present invention one of these plates, say the plate 7 may be made practically permanent with the base while the other plate, say the plate 8 is made so as to be readily detached when desired. These two plates are made to lie 75 in parallel relation under ordinary circumstances with a sheet 9 of insulating material separating them, so that the two plates 7 and 8 are maintained out of electrical contact. The plate 8 may be connected to the 80 conductor 6 through a narrow terminal band 10 so that when desired the plate 8 may be bent to one side and because of the attenuated character of the connecting band 10, the latter may be easily broken off and the 85 plate 8 thrown away after which the insulating lamina 9 may be removed thus exposing the plate 7.

Let it be assumed that the lamp in ordinary use is screwed into the usual socket 90 then a circuit is established between the walls of the socket and the screw member of the base and from thence through the leading-in wire or conductor 4 to the filament and through the latter to the conductor 6 and 95 thence by way of the neck 10 to the plate 8 and to the other terminal of the base. When the circuit is completed by the lamp switch or otherwise then the portion of the filament included between the conductor 6 and the 100 conductor 4 will glow in the usual manner while the other portion of the filament, that is the portion between the conductors 5 and 4 is out of circuit and therefore inert for light giving purposes. Now let it be assumed that either because of use or from 105 accidental causes the portion of the filament 2 between the conductors 4 and 6 becomes

burned out or otherwise broken. Under such conditions a lamp as ordinarily constructed becomes useless and must either be thrown away or renewed at considerable expense. When such a condition arises with the lamp shown in the drawings then the plate 8 is simply bent out of the way and moved back and forth a few times until the neck 10 becomes broken when the plate may be thrown away and the disk 9 of insulating material may be removed. Now the lamp may be replaced in the socket and the plate 7 will come in contact with the corresponding terminal in the socket and the circuit will be established at this point. The circuit will find a path through the leading-in conductor 4 to the unbroken or unburned portion of the filament thence out through the leading-in conductor 5 to the plate 7. The new portion of the filament having been unused will under ordinary conditions have as long life as the first portion of the filament and therefore the lamp as a whole has twice the life of an ordinary two-terminal lamp.

In external appearance the lamp has all the characteristics of an ordinary lamp but will give twice the service of an ordinary lamp without requiring any modification whatsoever in the ordinary lamp socket, while the only difference between the ordinary lamp and the improved lamp is in the addition of an extra central terminal for the base which may be quickly removed at will and without the aid of tools of any kind.

The extra cost of applying the improvement to lamps in the course of manufacture is so inconsiderable as to be nearly negligible and no change in the ordinary parts of the lamp is necessary. Furthermore, the improved lamp requires no change whatsoever in the lamp receiving socket or other members, and any person however unskilled may readily renew the operative condition of the lamp should the filament being used become burned out.

In Fig. 1 the filament is shown in the form of a double loop, with each loop constituting an individual light giving member.

In Fig. 3 the filament is shown as formed of two double loops instead of two single loops as in Fig. 1. This will illustrate the use of the invention for different forms of filaments and may be taken as indicative of any type of filament desired.

While the lamp is shown as provided with two terminal plates 7 and 8 only it will be

understood that more such plates properly insulated one from the other and a correspondingly greater number of active filament sections may be employed as may be found expedient. Of course it will be understood that distinct filaments may be used instead of filament sections and so by the expression "a plurality of filaments," or "a multiple filament" will be understood as meaning either a single filament connected up to the leading-in conductors to constitute a number of active sections, or a plurality of distinct filaments coupled up in like manner.

What is claimed is:—

1. An incandescent lamp having a plurality of filaments and an equal number of like external terminals for the filaments insulated one from the other and all in the longitudinal axis of the lamp.
2. An incandescent lamp having a plurality of filaments and an equal number of like external terminals for the filaments in the form of plates insulated one from the other and one parallel with the other and all in the longitudinal axis of the lamp.
3. An incandescent lamp having a plurality of filaments and an equal number of like external terminals for the filaments in the form of plates insulated one from the other and parallel one with the other and all in the longitudinal axis of the lamp, an outer plate and adjacent insulation being readily removable to expose the plate thereunder.
4. An incandescent lamp having a plurality of filaments and an equal number of like external terminals for the filaments in the form of plates one overlying and insulated from the other, the overlying plate and adjacent insulation being readily removable to expose the underlying plate.

5. An incandescent lamp having a plurality of filaments and an equal number of like external terminals for the filaments, one terminal overlying and being insulated from the other and readily removable together with the insulating material to expose the underlying terminal.

In testimony that I claim the foregoing as my own, I have hereto affixed my signature in the presence of two witnesses.

CHARLES I. DODSON.
